(57) **CLAIM**

The ornamental design for a cooling device for a rocket engine nozzle as shown and described.

DESCRIPTION

1. Cooling device for a rocket engine nozzle

FIG. 1.1: Front perspective view of a cooling device for a rocket engine nozzle.

FIG. 1.2: Front view thereof.

FIG. 1.3: Rear view thereof.

FIG. 1.4: Plan view thereof.

FIG. 1.5: Bottom view thereof.

FIG. 1.6: Cross-sectional view thereof taken through front to back center, and sectioned horizontally at the center of the front view.

FIG. 1.7: Cross-sectional view thereof taken through front to back center, and sectioned horizontally at the center of the plan view.

FIG. 1.8: Cross-sectional view thereof taken through front to back center, and sectioned horizontally at the center of the plan view.

FIG. 1.9: Cross-sectional view thereof sectioned vertically at the center of the plan view.

FIG. 1.10: Right side view thereof.

FIG. 1.11: Left side view thereof.

This product is a cooling device for a rocket engine nozzle, and more specifically, is a nozzle case for cooling the nozzle from the outside. The broken lines in the drawings illustrate portions of the cooling device for a rocket engine nozzle that form no part of the claimed design.
